UNITED STATES PATENT OFFICE.

JACOB SMITH, OF LEBANON, PENNSYLVANIA.

PROTECTING APPARATUS FOR BANKS OR THE LIKE.

Application filed March 30, 1921. Serial No. 457,078.

To all whom it may concern:

Be it known that I, JACOB SMITH, a citizen of the United States, residing at Lebanon, in the county of Lebanon and State of Pennsylvania, have invented certain new and useful Improvements in Protecting Apparatus for Banks or the like, of which the following is a specification, reference being had to the accompanying drawings.

10 This invention relates to certain improvements in protecting apparatus for banks or the like, and it is an object of the invention to provide an apparatus of this general character having novel and improved means 15 wherein the room or space occupied by employees may be closed against access by any person or persons outside of said space or room.

Another object of the invention is to provide a novel and improved device of this general character embodying a partition defining a space or room to be occupied by employees and in which money or other valuables are located and which partition 25 comprises a grid including normally open slats, together with means releasable at the will of a person within such room or space to swing or move said slats into closed position.

30 An additional object of the invention is to provide an apparatus of this general character adapted for use in connection with a room provided with a door or entrance opening and with which door or entrance opening 35 coacts a normally open door and wherein novel and improved means are provided releasable at will for causing said door to move into a closed position to prevent exit through said opening.

40 It is also an object of the invention to provide a novel and improved apparatus of this general character adapted to be employed in connection with a partition or wall provided with a window for a teller or the like and wherein novel and improved means are provided and releasable at will for closing said window.

Furthermore, the invention has for an object to provide a novel and improved apparatus of this general character embodying a grid comprising a series of normally open shutters, together with means releasable at

will for moving said shutters into closed position and wherein means are provided for coaction with the shutters when in closed position to hold the same against being moved into open position.

The invention consists in the details of construction and in the combination and arrangement of the several parts of my improved protecting apparatus for banks and the like whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in side elevation and partly in section illustrating an apparatus constructed in accordance with an embodiment of my invention;

Figure 2 is an enlarged fragmentary view partly in elevation and partly in section, the line of section being substantially at right angles to that in Figure 1;

Figure 3 is a fragmentary view in top plan of the structure as disclosed in Figure 1, with portions broken away;

Figure 4 is an enlarged sectional view taken substantially on the line 4—4 of Figure 1;

Figure 5 is an enlarged sectional view taken substantially on the line 5—5 of Figure 1;

Figure 6 is a fragmentary view in perspective illustrating a mounting for the movable or swinging member operable at will to release the closing elements;

Figure 7 is an enlarged sectional view taken substantially on the line 7—7 of Figure 1;

Figure 8 is an enlarged fragmentary view partly in section and partly in elevation illustrating the means herein disclosed whereby the closing elements may be released at will from a single station;

Figure 9 is an enlarged fragmentary sectional view taken substantially on the line 9—9 of Figure 2;

Figure 10 is an enlarged fragmentary view partly in section and partly in elevation illustrating in detail a member for closing a window for a teller or the like;

5 Figure 11 is a fragmentary view partly in horizontal section and partly in top plan illustrating in detail a means whereby the movement of one swinging member may be transmitted to the mechanism associated 10 with a second swinging or moving member; and

Figure 12 is a view in top plan of the normally open door coacting with the doorway or entrance opening.

15 As disclosed in the accompanying drawings, R denotes a room of desired dimensions and which is provided in one of its walls 1 with a door or entrance opening 2, said opening 2 having normally coacting therewith a door 3 of a conventional type. Each 20 vertical wall or stile of the opening 2 has extending therealong a guideway 4 in which is adapted to slidably engage a side marginal portion of an emergency door 5. This 25 door 5 may be of metal or other suitable material.

The door 5 also moves downwardly through an opening 6 in the floor 7 of the room and is normally held at the limit of 30 its downward movement. The downward movement of the door 5 is limited by the crown member 8 secured to the upper edge of the door 5 and which crown member 8, when the door is at the limit of its downward movement, serves as a sill for the 35 opening 2. The lower portion of the door 5 at substantially its transverse center is provided with an outstanding lug 9.

Normally overlying the upper face of 40 the lug 9 is an end portion of a latch bar 10, said bar being pivotally supported substantially midway its length, as at 11, for swinging movement in a horizontal direction. The latch bar 10 coacts with the lug 9 to maintain the door 5 at the limit of its downward movement.

Secured, as at 12, to the upper face of the lug 9 is an end portion of a flexible member 14. This member 14 extends upwardly 45 and passes over a roller 15 rotatably supported adjacent the floor 7. The opposite end portion of the member 14 is secured to a member 16 of a weight in excess of the weight of the door 5 and that portion 55 of the member 14 extending from the lug 9 to the roller 15 when the door 5 is at the limit of its downward movement. When the latch bar 10 is moved into position free from the lug 9, the member 16 operates 60 to automatically raise the door 5 into a position to close the opening 2.

The member 16 rests upon and has sliding movement on a guide plate 17 disposed on a downward and inward incline and extend-

ing from a point in close proximity to the 65 guide roller 15 to the floor 18 of the cellar or room C below the room R. This guide plate 17 operates to prevent the member 16 contacting with or otherwise obstructing the movement of the latch bar 10.

70 The end portion of the latch bar 10 remote from the door 5 has secured thereto, as at 19, an end portion of a flexible member 20. This member 20 extends inwardly in a horizontal direction from the latch bar 75 10 and passes upwardly and under a guide roller 21 rotatably supported by the adjacent wall 22 of the cellar or room C. The member 20 then extends upwardly and over a guide pulley 23 supported by the floor 7. 80 From the pulley 23, the flexible member 20 extends to and below a guide roller 24 supported by the floor 7 at a predetermined distance therebelow.

85 The adjacent end of the member 22 is secured to an extremity of an elongated arm 25, said arm 25 being supported substantially midway its length, as at 26, for rocking movement in a vertical direction. The end portion of the elongated arm 25 90 remote from the roller 24 is provided with a head 27 upon which is adapted to drop a weighted member 28. The member 28 is of such weight that the impact thereof, when dropped, upon the head 27 will rock 95 the arm 25 sufficiently to impose requisite pull upon the flexible member 20 to swing the latch bar 10 out of engagement with the lug 9, whereupon the door 5 is free to move upwardly into closed position under the 100 influence of the weighted member 16.

95 Secured, as at 29, to the lower marginal portion of the door 5 is an end portion of a flexible member 30 which extends downwardly and beneath the guide pulleys 21 105 spaced apart in a direction transversely of the door 5. The member 30 extends upwardly from the outer guide pulley 31 and over a guide pulley 32 carried by the floor 7. From the pulley 32, the flexible member 30 extends beneath another guide pulley 33 carried by the floor 7 and upwardly through said floor to a winding drum 34. Upon requisite rotation of the drum 34 in one direction, the flexible member 30 is 110 wound thereupon and whereby the member 30 is caused to return the door 5 to the limit of its downward movement and when returned to such position, the latch bar 10 is 115 then engaged with the upper face of the lug 9 so that said door 5 is normally held 120 against upward movement.

125 Suitably positioned within the room R are the counters A herein disclosed as two in number and in right angular relation. In the present embodiment of my invention, these counters A, in connection with certain of the walls of the room, provide an

5 enclosure or space E in which are adapted to be stationed certain attendants or employees and in which enclosure is also adapted to be arranged valuables, such as money or the like. The counters A, as herein disclosed are of a type generally employed in banking establishments and in connection with which establishments my apparatus is particularly adapted for use.

10 Extending upwardly from the counters A is a superstructure S which includes the vertically disposed shutters or slats 35. The shutters or slats 35 each have swinging movement about a vertical axis and each of 15 said shutters is of such width as to partially overlap adjacent shutters when swung into closed position. Pivotaly engaged with the inner portions of the upper edges of the shutters or slats 35 comprised in a series arranged above each of the counters A is an 20 operating bar or rod 36 whereby said series of shutters are caused to swing in unison and in the same general direction.

25 Coacting with the bar 36 is a retractile member 37, herein disclosed as a coil spring, and which retractile member serves to constantly urge the bar or rod 36 in a direction to swing the shutters or slats 35 into closed position. Coacting with an end shutter or slat 35 of each of the series of shutters or slats is a vertically swinging arm 38 each of which has an end portion constantly urged upwardly by the spring 39. When 30 the shutters or slats 35 of each series are in open position, an arm 38 partially overlies from below an end shutter or slat 35 whereby all of the shutters or slats in said series are held in their open position. Upon depression or downward movement of the arm 38, 35 the spring 37 automatically operates to throw all of said shutters or slats 35 into closed position.

40 When the shutters or slats 35 of each series are in their open position, an elongated 45 weighted bar 40 is supported upon the outer portions of the top edges of said shutters or slats. The bars 40 also are arranged inwardly of the vertically directed retaining brackets 41 which serve to prevent the bars 40 from being swung or moved outwardly 50 from the closed shutters or slats 35 whereby each of said bars 40 serves effectually to hold said shutters or slats 35 against being returned to open position until after the bar 55 40 has been elevated to a position above said shutters or slats 35.

55 Secured to the central portion of each of the bars 40 is a flexible member 42 which extends upwardly and pass around the suitably located guide pulleys 43. The members 42 constitute branches of a flexible member 44 which extends over a guide pulley 45 and downwardly to the drum 34 hereinbefore referred to so that, when said drum

34 is rotated to lower the door 5, both of 65 the bars 40 will be raised to a position above the shutters or slats 35 so that said shutters or slats can be returned to or moved back into open position. In order that the flexible members 30 and 44 will not interfere 70 one with the other, said drum 34 is provided at its central part with a dividing flange 46, the flexible member 30 winding upon said drum 34 at one side of the flange 46 and the flexible member 44 winding upon 75 the drum at the opposite side of said flange 46.

80 The superstructure S adjacent an end shutter or slat 35 of one of a series of said shutters or slats is provided with a horizontally disposed table or shelf 47 upon which is pivotally engaged a horizontally swinging arm 48. One end portion of the arm 48 is in the path of the adjacent end shutter or slat 35 when the same is swung 85 into closed position.

Extending upwardly from the weighted member 28 is a rod 49 and the upper end portion of the rod 49 is provided with a hook member or lateral extension 50 to engage the table or shelf 47 whereby the weight 28 is held in its raised or elevated position. The lateral extension or hook member 50 engages the shelf 47 at a point adjacent the tail portion of the horizontally swinging 95 arm 48 when said arm 48 is in its normal position or in a position when said tail portion overlies the table or shelf 47.

When the shutters or slats 35 are automatically moved or swung into their closed 100 position, an end shutter or slat of one of the series strikes the swinging arm 48, resulting in the tail portion of said arm throwing the lateral extension or hook member 50 off from the table or shelf 47 whereupon the 105 weighted member 28 is free to drop upon the head 27 for a purpose hereinbefore explained.

110 The working or upper end portion of each of the arms 38 has operatively engaged therewith, as at 51, an end portion of a depending rod 52. The lower end portion of the rod 52 is operatively engaged, as at 53, with an elongated strip or bar 54. Each end portion of the bar 54 is provided to one 115 side of the transverse center of said bar with a trunnion 55 whereby the bar 54 is supported for rocking movement so that, upon rocking or swinging movement of the bar 54 in one direction, the co-acting latch 120 51 will be pulled downwardly out of engagement with a shutter or slat 35.

125 The connection 53 is with the outer edge or marginal portion of the bar 54 and said outer marginal portion of the bar 54 adjacent the opposite ends thereof is provided with the depending arms 56 connected at their lower end portions by the foot board 57. The

foot board 57 is constantly urged outwardly by one or more suitably positioned springs 58. When a person within the enclosure E forces, as by the foot, a foot board 57 inwardly, the coacting arm 38 is moved downwardly so that the shutters or slats 35 will automatically close.

It is of particular advantage and benefit that all of a series of shutters or slats 35 automatically close upon pressure being imposed upon any one of the foot boards 57. Positioned below each of the bars 54 is a bell crank lever 59 in the form of an inverted L and the upper horizontal arm 60 of said lever is operatively engaged through the rod 61 with a rock arm 38 so that, as the arm 38 is moved downwardly, the vertical arm 62 of the bell crank lever will be swung in a direction toward the succeeding or second bar 54.

The lower end portion of the arm 62 of the bell crank lever 59 is operatively engaged by the rod 63 with an end portion of the succeeding or adjacent foot board 57 so that, as one rock arm 38 is swung downwardly, the second foot board 57 will be forced inwardly so that both of the rock arms 38 will have downward movement in unison whereby both series of shutters or slats 35 are released.

In the present embodiment of my invention, the lower portion of each of the superstructures S is provided with a window 64 and the sill of said window is provided with an opening 65 through which is adapted to move a closure member or door 66. The door 66 is normally held at the limit of its downward movement and when in such position the top of the door 66 is substantially flush with the sill of the window 64. The lower portion 66^a of the door 66 is reduced in thickness to overlap an inwardly directed block 67 carried by the adjacent counter A, the outer face of said block being provided with the guides 68 coacting with the reduced portion 66^a so that said door or closure 66 is supported for substantially direct endwise movement in a vertical path. The reduced portion 66^a of the door or closure 66 is provided with an inwardly directed rib 69 and an outwardly directed rib 70 carried by the lower portion of the block 67 is an expansible member or spring 71 which operates to constantly urge the door or closure 66 upwardly.

The outer face of the reduced portion 66^a is provided with a pocket or recess 72 in which engages an angular finger 73 carried by an inverted U-shaped frame 74, the side arms 75 of which are pivotally engaged, as at 76, intermediate their ends with the side faces of the block 67. The lower end portions of the side arms 75 terminate rearwardly of the adjacent foot board 57 so that,

when said foot board 57 is forced inwardly, 65 the frame 74, or more particularly the upper portion thereof, is swung outwardly so that the finger 73 is disengaged from the portion 66^a of the closure or door 66 so that said door or closure is free to have 70 upward movement into closed position under the influence of the expansible spring 71.

Each of the members 63 hereinbefore referred to is operatively engaged with an arm 77 comprised in a bell crank lever 78. 75 The second arm 79 of the lever 78 overlies a side arm 75 of the frame 74 below the pivotal mounting 76 so that, when the foot board 57 coacting with one of the counters A is swung inwardly to effect the desired 80 closing operations, it will be assured that the frame 74 of the second counter will be rocked sufficiently to release the door 66. This supplemental means for moving the frame 74 has been found of advantage in 85 view of the fact that upon inward movement of one of the foot boards 57, the second foot board 57 is not moved inwardly sufficiently to effect the desired releasing movement of the frame 74 coacting with said 90 second foot board.

Suitably arranged within the enclosure E is a desk or station D and which station is adapted to be occupied by a person who can have ready supervision of all the counters, and arranged at said desk or station is a lever 80 extending through the floor 70, the pivoted end portion of the lever being continued by the upwardly directed pedal 81. The lower end portion of the lever 80 100 has operatively engaged therewith the rod 82 which is also operatively engaged with a lever 83 supported for swinging movement and extending through the floor 7. This lever 83 has an upwardly disposed extension 84 in contact with a foot board 57. When the occasion arises whereby it is necessary that the various closure members be moved into closed position, the person at the desk or station D presses upon the pedal 110 81 whereupon the upper or extended portion 84 of the lever 83 forces the coacting foot board 57 inwardly a distance sufficient to release the different closure members so that they may move into closed position. 115

Should a person enter the room R for the purpose of robbery or other unlawful acts, as soon as any person within the enclosure E becomes aware of this fact, it is only necessary for this person either to force inwardly 120 a foot board 57 or impose pressure upon the pedal 81 and whereupon the shutters or slats 35 and the closure members or doors 66 will move into closed position and at the same time the door 5 will be released and move 125 upwardly into closed position so that said person is held against exit. When the shutters or slats 35 are in closed position, a per-

son outside of the enclosure E is unable to insert a firearm through the superstructure nor is he able to fire upon a person within the enclosure E or otherwise have access 5 therein. In view of this, it will at once be obvious that my improved apparatus is not only effective in preventing robbery and injury of the persons within the enclosure E but also provides means whereby such 10 lawful person is held against escape so that his capture may be facilitated.

From the foregoing description it is thought to be obvious that a protecting apparatus for banks or the like constructed 15 in accordance with my invention is particularly well adapted for use by reason of the convenience and facility with which it may be assembled and operated, and it will also be obvious that my invention is susceptible 20 of some change and modification without departing from the principles and spirit thereof and for this reason I do not wish to be understood as limiting myself to the precise arrangement and formation of the several 25 parts herein shown in carrying out my invention in practice except as hereinafter claimed.

I claim:

1. An apparatus of the class described comprising, in combination with a counter, 30 slats supported above the counter for swinging movement, said slats overlapping when moved in one direction, a member connecting said slats for movement in unison and in the same direction, means for constantly 35 urging the slats into closed position, means releasable at will for holding the slats in open position, and a weighted member supported by the slats when said slats are open, 40 said member dropping into a position to overlie the slats when closed to hold the slats against opening movement.

2. An apparatus of the class described comprising, in combination with a counter, 45 slats supported above the counter for swinging movement, said slats overlapping when moved in one direction, a member connecting said slats for movement in unison and in the same direction, means for constantly 50 urging the slats into closed position, means releasable at will for holding the slats in open position, a weighted member supported by the slats when said slats are open, said member dropping into a position to overlie 55 the slats when closed to hold the slats against opening movement, and means for moving said member in a position to permit the slats to be opened.

3. An apparatus of the class described 60 comprising, in combination with a counter, slats supported above the counter for swinging movement, said slats overlapping when moved in one direction, a member connecting said slats for movement in unison

and in the same direction, means for constantly urging the slats into closed position, 65 means releasable at will for holding the slats in open position, a member resting upon the upper ends of the slats when open, said member dropping by gravity when the slats are 70 closed into a position to hold the closed slats against opening movement, and means for holding said member against movement in a direction away from the slats.

4. In combination with a wall provided 75 with an opening, a door co-acting with said opening, means operating automatically to move the door into closed position, means for holding the door in open position, a counter, 80 slats supported above the counter, means for moving the slats into closed position, a suspended weight member, means operable upon movement of the slats into closed position to release the weighted member, and means operated by said member when released to release the means for holding the door in open position.

5. In combination with a wall provided 85 with an opening, a door co-acting with said opening, means to move the door into closed 90 position, a counter, slats supported above the counter for swinging movement, means for urging the slats into closed position, a weighted member supported by the slats 95 when said slats are in open position, said member dropping into a position to hold the slats against opening movement, and means operatively engaged with the door and with the weighted member to raise the weighted member and to move the door into 100 open position.

6. In combination with a counter, an apparatus of the class described comprising a plurality of series of swinging slats, means co-acting with each of said series of slats for automatically moving said slats into closed position, a member co-acting with each of the series of slats for holding the slats in open position, means for moving each of 105 said members in a position to permit the co-acting series of slats to close, and an operative connection between each of the last named members whereby the operation of one of said means causes all of said means to operate in unison.

7. In combination with a counter, a plurality of slats positioned thereabove for swinging movement, a member connecting the slats for movement in unison in the same general direction, a movable member for 110 holding the slats in open position, automatic means for holding the slats in closed position when said movable member is inoperative, a foot rail supported for swinging movement, an operative connection between the 115 said rail and the movable member to shift said movable member into inoperative position upon movement of the rail in one direc-

tion, said counter including a window, a closure member co-acting with said window, means for automatically moving said closure member into closed position, and a latch for holding said closure member in open position, said latch being released from the closure member by contact of the foot rail

with said latch when said rail is moved in a direction to shift the movable member into inoperative position. 10

In testimony whereof I hereunto affix my signature.

JACOB SMITH.
